UNITED STATES PATENT OFFICE.

NORVIN H. FRANKS, OF CHICAGO, ILLINOIS, ASSIGNOR TO CABRANETTE CORPORATION, OF CHICAGO, ILLINOIS, A CORPORATION OF ILLINOIS.

DESIGN FOR A COMBINED REFRIGERATOR AND CABINET.

Application filed July 29, 1921. Serial No. 488,482. Term of patent 14 years.

To all whom it may concern:

Be it known that I, NORVIN H. FRANKS, a citizen of the United States, residing at Chicago, in the county of Cook and State of Illinois, have invented a new, original, and ornamental Design for a Combined Refrigerator and Cabinet, of which the following is a specification, reference being had to the accompanying drawings, forming part thereof.

The figure is a perspective view of the combined refrigerator and cabinet.

I claim:

The ornamental design for a combined refrigerator and cabinet, as shown.

In testimony whereof, I have hereunto signed my name in the presence of two subscribing witnesses.

NORVIN H. FRANKS.

Witnesses:

ROY W. HILL,
RUTH M. EPHRAIM.
